THOMAS A. RIDDER, OF WHITMAN, MASSACHUSETTS

RADIATOR HANGER

Application filed May 27, 1929. Serial No. 366,169.

This invention relates to radiator hangers for supporting radiators from a wall of a building in spaced relation to the floor.

Many of the radiators now employed to heat buildings are mounted upon the walls of the building out of engagement with the floor. This form of radiator installation avoids the use of supporting legs resting upon the floor and around which dirt and dust tends to collect, and is neater in appearance.

In order to support radiator hangers or wall brackets from a wall of a building it is customary to install the anchoring bolts in the wall of the building when the building is being erected. It is difficult, however, to determine at this time the exact position at which the anchoring bolts should be located, and it is therefore desirable to so construct the hangers that the radiator engaging portion thereof may be adjusted in different planes relative to the fixed anchoring bolt to facilitate the proper positioning of the radiator.

While adjustable radiator hangers have been proposed heretofore, they have been comparatively complicated in construction and expensive to manufacture.

The present invention therefore relates to a simple form of radiator hanger which consists of comparatively few parts that are inexpensive to manufacture and assemble, and which permit adjustment of the radiator engaging element in three different planes with respect to the fixed anchoring bolt to facilitate the proper setting of the radiator.

A further feature of the present invention resides in radiator hangers which are constructed to form a firm, stable mounting for the radiator, and which will also be well concealed from view of the radiator they support.

Other features of the invention and novel combination of parts in addition to the above will be hereinafter described in connection with the accompanying drawings, which illustrate one good practical form of the invention.

In the drawings,—

Fig. 1 is a front elevation of a radiator having associated therewith hangers form-

ing the subject matter of the present invention;

Fig. 2 is a sectional view taken on the line 2—2 of Fig. 1, through the radiator and a portion of the supporting wall;

Fig. 3 is a perspective view showing the hanger elements in disassembled relation;

Fig. 4 on a smaller scale is a front elevation of a hanger; and

Fig. 5 on a large scale is a vertical sectional view through cooperating parts of the hanger.

The radiator hanger forming the subject matter of the present invention may be employed to support from the wall of a building practically any type of radiator used for heating purposes, and the supported radiator may be formed of any desired number of sections each of which may have two or more tubes or columns. In most cases two radiator hangers will be sufficient to support a radiator, but if the radiator is exceptionally long, three or possibly more radiator hangers may be employed to support the same at the desired elevation from the floor.

In Figs. 1 and 2 of the drawings are shown a steam or water radiator of well known construction, and consisting of the radiator sections 10 which are secured together by the usual through rods 11, and each section 10 is shown as constituting a four-tube construction having the connecting nipples 12.

The means commonly employed for securing radiator hangers to a wall 13 of a building consists of the anchoring bolts 14 which preferably are mounted in the wall when the building is being erected and the outer end of these bolts are threaded as shown, while the inner end of each bolt may be bent as at 15, or otherwise constructed, to cause the bolt to be firmly anchored in the wall 13.

While these anchoring bolts should be positioned as accurately as can be readily determined where they will be needed to support a radiator, it is difficult to determine, at the time the walls are being constructed, the exact position in which such bolts should be located to support a radiator, and it is therefore desirable to so construct the radiator hangers that the radiator engaging portion

thereof may be adjusted in various planes relative to the supporting bolt 14 to facilitate installation of the radiators.

Having this in mind, the present invention 5 relates to a simple and inexpensive form of radiator hanger which is so constructed that the radiator engaging arm to be described may be adjusted in three different planes relative to the supporting bolt 14. As a result 10 of these various adjustments, the radiator supporting arm may be raised or lowered to vary the height of the radiator, may be adjusted laterally with respect to the bolt 14 to facilitate the introduction of the supporting 15 arm between adjacent sections 10, and may be moved towards and from the wall 13 to accommodate radiators of different widths, all of which will be more fully described herein.

One of the elements of the radiator hanger 20 of the present invention consists of a wall plate 16 which is shown as having an upwardly extending portion 17 in which portion is formed an elongated slot 18 adapted to receive the anchoring bolt 14. By giving the 25 bolt receiving opening 18 the elongated construction shown, the plate 16 may be raised and lowered to the desired position of adjustment and clamped in its adjusted position by tightening the nut 19 against the washer 20. 30 The outer face of the portion 17 of the bracket and the inner face of the washer 20 are preferably provided with the cooperating teeth 21 adapted to prevent slippage between these parts after they have been clamped in 35 place. The wall plate 16 is shown as having a flat rear face adapted to rest firmly against the wall 13 of the building and near the lower end of this wall plate may be provided a rearwardly projecting pin 22 adapted to project 40 into the wall 13 sufficiently to prevent the plate 16 from swinging about the anchoring bolt 14 as a pivot.

The wall plate 16 serves to support a bracket 23 which extends frontwardly from the wall plate and as above stated it is desirable that this bracket be mounted for adjustment transversely of the plate 16. This is accomplished in the construction shown by providing the bracket 23 with an offset upwardly extending tongue 24 which is adapted 45 to project through a transversely extending slot 25 formed in the wall plate 16 and abut against a wall 26 of the wall plate, which wall 26 is spaced inwardly somewhat from the 50 rear face of the wall plate 16, as will be apparent from Fig. 5. The tongue receiving slot 25 is made sufficiently long to permit the bracket 23 to be adjusted a substantial distance transversely of the wall plate 16 while 55 the parts are in locking engagement with each other, as shown in Fig. 5, the tongue engaged wall 26 being spaced from the wall of the building 13 sufficiently to provide a clearance space for the tongue 24.

60 The tongue 24 may be moved to the bracket

supporting position in which it is shown in Fig. 5 by tilting the outer end of this bracket upwardly to facilitate insertion of the tongue 24 through the slot 25, whereupon the bracket 23 may be swung downwardly to its normal vertical position in which it is shown in the drawing so that the under face of the curved tongue 24 will rest upon the supporting shoulder 27 of the wall plate as shown, and an abutment 28 provided at the lower end of the bracket 23 will rest upon the lower outer face of the wall plate 16 to support the bracket 23 in its vertical position.

It is usually deemed advisable to support the inner face of the radiator a predetermined distance from the building wall 13 irrespective of the thickness of the radiator; the inner faces of such radiators being frequently spaced an inch and three quarters from the supporting wall 13.

In the construction shown, the bracket 23 is provided with an upwardly extending arm 29 having a concaved seat 30 formed in its upper end and shaped so that a relatively small nipple 12 may rest in the seat 30 as shown, while a larger nipple will rest upon the ends of the projections provided at the upper end of the arm 29 to support the radiator. The upper end of the arm 29 is also preferably provided with a slot 31 constituting a clearance space for one or more tie rods 11.

Since, as above stated, it is customary to support the inner face of a radiator a predetermined distance from the wall of the building irrespective of the thickness of the particular radiator, it will be seen that the row of nipples 12 may lie different distances from the building wall 13, depending upon the thickness of the particular radiator to be supported. In order to meet this condition it is desirable that the upwardly extending arm 29 be mounted for adjustment towards and from the wall 13. This is accomplished in the embodiment of the invention illustrated by providing the frontwardly extending portion of the bracket 23 with the recess 32 adapted to slidably receive a correspondingly shaped portion 33 formed adjacent the lower end of the arm 29 and these 110 cooperating parts 32 and 33 are rigidly secured together in the desired position of adjustment by a bolt 34 the shank of which extends through an elongated slot 35 formed in the bracket 23. The arrangement is such 115 that the upwardly extending arm may be moved towards and from the wall plate 16 as may be required to properly support a particular radiator and may be clamped in the desired position of adjustment by tightening 120 the nut 36 upon the bolt 34.

When a radiator is supported by the hangers as above described, it may have a tendency to swing towards and from the wall 13 about the upper nipples 12. This may be prevented,

however, by providing the downwardly extending portion 23 of the bracket with the transversely extending bridge bar 37 which forms an abutment against which the inner face of the radiator may rest, as will be apparent from Fig. 2, to hold the latter from rocking about its pivotal support. This swinging movement of the radiator will be further prevented by the usual pipe connections provided to supply the heating medium to the radiator.

It will be seen from the foregoing that the entire radiator hanger of the present invention, with the exception of the clamping bolts, may be formed of castings which are easily constructed without requiring machining operations, and that the parts may be easily and quickly assembled ready for use. It will also be seen from the foregoing that the entire radiator hanger is so constructed that it will be well concealed when in use by the radiator itself.

What is claimed is:—

1. A radiator hanger, comprising in combination, a wall plate secured to a wall for vertical adjustment, a bracket provided with a tongue for removably securing the bracket to said plate so that the bracket may be readily disengaged from the plate without disturbing the position of the latter and an abutment on the bracket adapted to engage the plate and to cooperate with said tongue to support the bracket for lateral adjustment upon the plate, a steady rest upon said bracket for engagement by the rear face of a radiator, and a radiator supporting arm adjustably mounted upon said bracket and supported by the bracket and wall plate for adjustment in the three geometric planes.

2. A radiator hanger, comprising in combination, a wall plate secured to a wall for vertical adjustment and provided with a transversely extending slot, a bracket provided with a tongue for removably securing the bracket to said plate and adapted to engage a portion of the plate at the rear of said slot, an abutment on the lower portion of said bracket adapted to rest against the front face of said plate and to cooperate with said tongue to support the bracket for lateral adjustment upon the plate, a steady rest upon said bracket for engagement by the rear face of a radiator, and a radiator supporting arm slidably secured to said bracket for adjustment relative to said steady rest and supported by the bracket and wall plate for sliding adjustment in the three geometric planes.

3. A radiator hanger, comprising in combination, a wall plate secured to a wall for vertical adjustment and provided with a transversely extending slot, a bracket provided with a tongue adapted to enter said slot and rest on the lower edge thereof and provided with an upwardly turned end por-

tion that abuts against a portion of said plate at the rear of said slot and serves to removably secure the bracket to the plate, an abutment on the lower portion of said bracket adapted to rest against the front face of the plate and to assist said tongue in supporting the bracket for lateral adjustment upon the plate, and a radiator supporting arm adjustably secured to said bracket and supported by the bracket and wall plate for adjustment in the three geometric planes.

In testimony whereof, I have signed my name to this specification.
